DESIGN FOR A DINNER DRESS PAJAMA

Abraham H. Morris, New York, N. Y.

Application November 19, 1938, Serial No. 81,238

Term of patent 3½ years

To all whom it may concern:

Be it known that Abraham H. Morris, a citizen of United States and resident of New York city, in the county of New York, State of New York, has invented a new, original, and ornamental Design for a Dinner Dress Pajama, of which the following is a specification, reference being had to the accompanying drawing, forming part thereof, and in which,

Fig. 1 is a front view of a dinner dress pajama, embodying my new design; and

Fig. 2 is a rear view of the same.

I claim:

The ornamental design for a dinner dress pajama, substantially as shown.

ABRAHAM H. MORRIS.
